UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

REVERSING MOTION FOR LOOM LET-OFFS.

Application filed July 27, 1925. Serial No. 46,282.

This invention relates to let-off motions for looms and more particularly to means for reversing the warp at the time of a pick-out so that the cloth may be let back the proper distance before weaving is resumed.

In the weaving of fabrics such as duck a defective pick of filling is occasionally woven into the fabric and it is necessary for the weaver to "pick out" or reverse the picking operations to remove all picks which were laid after the imperfection occurred. When this step is completed the fell of the cloth must be moved back to the reed line and it is desirable that the warp threads be under the same tension as that which prevailed before the "pick out".

It is accordingly the principal object of my invention to employ the usual and well-known adjusting mechanism for the friction of the left-off in such a way that said mechanism may be released from its normal position and used to reverse the warp, whether the latter be delivered by a beam or the drum usually employed in connection with a creel.

A more detailed object of my invention is to mount the usual friction band on members which are normally stationary but which may be moved at will in one direction to slacken the band so that the same may take a fresh hold on the friction drum and then be moved in the other direction to tighten the band on the drum and cause a partial rotation of the latter.

With these and other objects in view which will appear as the description proceeds, my invention resides in the combination and arrangement of parts hereinafter described and set forth in the claims.

In the accompanying drawings where I have shown my invention as applied to a duck loom having a delivery drum such as is used in conjunction with a creel.

Fig. 1 is a vertical section through the loom intermediate the loom sides and showing the device in normal operating position,

Fig. 2 is a view similar to Fig. 1 but showing the position the parts assume when a rewinding motion is to be given the drum,

Fig. 3 is a section on line 3-3 of Fig. 1,

Fig. 4 is an enlarged side elevation of the pawl which aids in preventing retrograde movement of the drum, and

Fig. 5 is a detail vertical section through the locking pin showing the same in locking position.

Referring more particularly to the drawings it will be seen that I have provided a loom frame 10 having a warp delivery drum 11 the end of which has secured thereto a gear 12 meshing with a pinion 13. Said pinion 13 is secured to a cross shaft 14 on which is fixed in any approved manner a drum 15. A flexible friction band 16 surrounds a portion of the drum 15 and has one end thereof anchored to a normally fixed stud 17 and the other end secured to a stud 18 carried by a lever 19.

At the front of the loom there is provided the usual vertical screw 20 movable between 70 bearings 21 secured to the loom side and rotatable by means of a hand wheel 22. A block 23 is loosely mounted on the screw 20 and is moved up and down as the latter is rotated. Said block is provided with a 75 notch 24 which supports the forward end of the lever 19 so that as the screw is turned the band 16 will be tightened or loosened to increase or diminish the friction on the drum 15. The matter thus far described is 80 of common construction and introduces no departure over devices well known in the art.

My improvements relate to means for moving the friction band as a whole about 85 the axis of the drum 15 to the end that the strap may be slackened when handle 19 is moved down and may be tightened when said handle is raised. In carrying out my improvements I provide an arm 30 which is pivoted on the shaft 14 and carries the normally fixed stud 17. The handle 19 is pivoted to said arm as at 31 and said arm is provided with an opening 32 normally occupied by a pin 33 shown in detail in Fig. 5. 90 A lever 34 is pivoted as at 35 to the loom frame and has a cam face 36 positioned for engagement with the head 37 of the pin 33. A spring 38 acts normally to move the pin 95 out of the opening 32 but is held from doing so by the broad part of the lever 34 which engages the head 37 to hold said pin in the opening 32.

The rear end of lever 34 has pivoted thereto a pawl 39 which is normally supported by a lug 40 formed on the lever 34

and so long as the latter is in normal position the pawl will be held above the ratchet wheel 41 rigid with the drum 15. Foot lever 42 moves about a fixed pivot 43 and is connected by an adjustable upright rod 44 to lever 34 so that as the foot lever is depressed the pawl will be lowered into operative relationship with respect to the ratchet and the cam face 33 formed on lever 34 will be raised to permit spring 38 to withdraw the pin 33 from the opening 32.

Under normal conditions the pin 33 is in the opening 32 so that both studs 17 and 18 are in fixed position and any adjustments of lever 19 will be communicated directly to the friction band 16. At the time of picking out lever 19 will be flexed off block 24, after which foot lever 42 will be depressed to permit the withdrawal of pin 33 from opening 32. This unlocks arm 30 and permits the same to move freely about shaft 14. Lever 19 will now be moved downwardly by the operator, this action being accompanied by a downward movement of the arm 25 30 and a slackening of the band 16. The pawl 39 will also fall into operative position with respect to ratchet 41. Should the band stick and tend to hold the arm 30 raised, a finger 45 on lever 19 will engage 30 a boss 46 on said arm and positively lower said arm. When the lever 19 has been lowered sufficiently the operator will raise the same, which will result in a tightening of 35 the band 16 about the friction drum and cause a reverse motion of the warp delivery drum. This operation may be repeated as often as necessary to restore the fell of the cloth to the reed line, after which the lever 19 may be sprung over the notch 24, 40 the pin 33 having previously been inserted in the opening 32 by the release of foot lever 42. The parts are thus restored to their normal position and the friction is the same after the pick-out as it was before.

45 From the foregoing it will be seen that I have provided a simple device for reversing the warp of the loom by the simple manipulation of the hand lever usually employed in the type of loom to which the invention relates and that the friction is the same after the pick-out as it was before.

Having thus described my invention it will be apparent that changes and modifications may be made therein by those skilled in the art without departing from the spirit and scope of the invention, and I do not wish to be limited to the details herein disclosed but what I claim is:

60 1. In a let-off mechanism for a loom having a warp delivery means and a friction surface operatively connected therewith, a friction band cooperating with the friction surface to retard movement of the warp delivery means, normally stationary means to support said band and hold the same in

close contact with the friction surface, and means to move said band as a whole in one direction about the axis of the friction surface to an abnormal position to slacken said band and in the opposite direction to tighten 70 said band while in the abnormal position and to thereafter restore said band to normal position.

2. In a let-off mechanism for a loom having a warp delivery means and a friction surface operatively connected therewith, an arm movable about the axis of the friction surface but normally locked in stationary position, a hand lever pivoted to said arm, means to adjust said lever with respect to the arm, a friction band having one end secured to the arm and the other end to said lever to cooperate with the friction surface and retard movement of the warp delivery means, said arm and hand lever being releasable from locked position to move in one direction to slacken the band and in the opposite direction to tighten the band around the friction surface.

3. In a let-off mechanism for a loom having a warp delivery means and a friction surface operatively connected therewith, an arm normally stationary but movable about the axis of the friction surface, a manually controllable lever pivoted to the arm, means for adjusting the position of the lever with respect to the arm, and a friction band in operative contact with the friction surface and having one end thereof secured to the arm and the other end secured to the lever, the arm and lever being movable from normal stationary position to move as a unit about the axis of the friction surface in one direction to slacken the friction band and movable as a unit in the opposite direction to tighten the band about the friction surface.

4. In a let-off mechanism for a loom having a warp delivery means and a friction surface operatively connected therewith, a pair of members pivotally connected together, one of said members being normally stationary but movable about the axis of the friction surface, and the other member adjustable with respect to the first named member, a flexible friction band cooperating with the friction surface to retard movement of the warp delivery means, said band having one end secured to one of the members and the other end secured to the other member, said members being movable from normal position to move as a unit about the axis of the friction surface in one direction to slacken the friction band and movable as a unit in the other direction to tighten 120 said band.

5. The method of causing reverse movement of loom warp delivery means having a rotary member movable with the delivery means and a friction band normally tightly 130

drawn around a portion of the rotary member, consisting in loosening the friction band with respect to the rotary member, moving the band as a whole angularly with respect 5 to the rotary member to an abnormal position, tightening the band with respect to the rotary member in the abnormal position, and returning the band so tightened to normal position to cause movement of the rotary member.

6. In a let-off mechanism for a loom having a warp delivery member and a friction surface operatively connected thereto and movable therewith, a friction band normally 15 in contact with the friction surface to resist advance movement of the warp delivery member, means to slacken the friction band and move the same as a whole to an abnormal position with respect to the friction surface, mechanism to prevent advance movement of the warp delivery member when the friction band is slackened with respect to the friction surface, said first named means effective to tighten the band around the friction surface and to thereafter restore the band from abnormal to normal position and simultaneously effect a reverse movement of the warp delivery member.

7. In a let-off mechanism for a loom having a warp delivery member and a friction surface operatively connected thereto and movable therewith, a normally stationary flexible friction element engaging the friction surface to resist advance movement of the warp delivery member, a device to support said element in normal position, mechanism to simultaneously release said element supporting device and to prevent advance movement of the warp delivery member, said 35 device when released slackening the element relatively to the friction surface and moving the same to abnormal position, said support thereafter being movable to tighten the element with respect to the friction surface and 45 then movable to return the element from abnormal to normal position to effect a reverse movement of the warp delivery member.

8. In a reversing mechanism for a loom warp delivery member having a friction surface operatively connected thereto and movable therewith, a flexible friction element for the friction surface, an arm to support one end of the element, a lever pivoted on the arm and attached to the other end of the element, a holding device for the arm to hold the latter normally in fixed position, and

means simultaneously to move the holding device out of holding position with respect to the arm and to prevent advance movement of the warp delivery member, said lever and 60 arm being movable to slacken the flexible element and moving the latter to an abnormal position, and said arm and lever thereafter being movable to tighten the element on the friction surface and being then movable to return said element from abnormal 65 to normal position to effect a reverse movement of the warp delivery member.

9. In a reversing mechanism for a loom warp delivery member having a friction surface operatively connected thereto and movable therewith, a flexible friction element for the friction surface normally serving to resist advance movement of the warp delivery member, and means to slacken the element 70 with respect to the friction surface and to thereafter move said element as a whole in a direction corresponding to an advance movement of the warp delivery member to an abnormal position, said means thereafter being 75 movable to tighten the friction element while in abnormal position and then movable to restore said element to normal position and effect a reversal of the warp delivery member.

10. In a reversing mechanism for a loom warp delivery member having a friction surface operatively connected thereto and movable therewith, a flexible friction element for the friction surface to resist advance movement of the warp delivery member, normally stationary but movable supporting means for the friction element, said supporting means being movable to slacken the friction element and thereafter moving said element 90 in a direction corresponding to an advance movement of the warp delivery member to an abnormal position, and mechanism to prevent advance movement of the warp delivery member when the element is moving 95 in a direction corresponding to an advance movement of the warp delivery member, said supporting means thereafter being movable to tighten the element with respect to the surface and then to move said element 100 from abnormal to normal position in a direction corresponding to a reverse movement of the warp delivery member.

In testimony whereof I have hereunto affixed my signature.

WALTER H. WAKEFIELD.
